CLAIM

The ornamental design of a pedicure foot spa, as shown and described.

DESCRIPTION

FIG. 1 is a top perspective view depicting a pedicure foot spa, showing my new design.

FIG. 2 is a bottom perspective view thereof;

FIG. 3 is a top perspective view depicting the pedicure foot spa, without the foot rest to show the extended edge around the basin.

FIG. 4 is a top perspective view depicting the foot rest, shown separated from the pedicure foot spa for ease of illustration.

FIG. 5 is a top plan view of the pedicure foot spa;

FIG. 6 is a bottom plan view thereof;

FIG. 7 is a front end elevation view thereof;

FIG. 8 is a side elevation view thereof; and,

FIG. 9 is a rear elevation view thereof.

The broken line showing of parts of the drawings is included for the purpose of illustrating use and environment and forms no part of the claimed design.
